UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC SWITCH.

1,254,713.

Specification of Letters Patent. Patented Jan. 29, 1918.

Application filed November 20, 1916. Serial No. 132,394.

To all whom it may concern:

Be it known that I, FRANK A. LUNDQUIST, a citizen of the United States, residing at New York, in the county of New York and State of New York, have invented certain new and useful Improvements in Automatic Switches, of which the following is a full, clear, concise, and exact description.

This invention relates to automatic switches for interconnecting telephone lines. It is adapted for use with either automatic or semi-automatic telephone exchange systems.

The object of this invention is to provide new and simple means for connecting a calling subscriber with an idle trunk leading either to an operator's position or to a first selector switch.

A feature of the invention is the mechanical stopping of a falling carriage with its contact arm resting on a selected movable terminal in such a way that the seizure of a terminal will immediately move the terminal into non-selectable position.

Referring to the drawings, Figure 1 shows a front elevation of a set of subscribers' terminal rods and strips, two trunk line carriages, the restoring mechanism and circuits by which the switches may be operated; and Fig. 2 shows an end elevation of the same, including the more important details.

In switches of the type herein disclosed, the terminals of subscribers' lines are represented by horizontal rods and strips, one of each being provided for each line, and the terminals of trunk lines are represented by pairs of vertical wires, which are mounted in groups of any desirable number before each set of subscribers' terminal rods and strips. A carriage normally held at the top of a pair of trunk wires, and in electrical connection with one of them, is released and allowed to fall under the attraction of gravity when a subscriber calls. The act of calling displaces the subscriber's terminal rod so that an arm, pivotally mounted on the falling carriage, will engage it, stopping the carriage and replacing the terminal rod so that it will not be seized by any other carriage which may fall. A metal strip, mounted on but insulated from the arm, makes connection between a contact spring on the subscriber's terminal strip, and the second wire of the trunk pair associated with the falling carriage. A connection is thus completed between a calling subscriber and a trunk line. At the end of the conversation,

the carriage is automatically lifted to its normal position by a third wire parallel to the trunk wires, and the trunk line is ready for use with the next call.

60

The construction of the switch will be more readily understood from the following detailed description. A frame, certain parts of which are shown in the drawings, supports each set of subscribers' terminal rods and strips, trunk wires, movable carriages and associated apparatus. The subscribers' terminal rods 102, in which terminates one side of each subscriber's line, are closely held near either end in holes 200 of the uprights 100. The rods are crank-shaped and tend to hang with the offset portion 103 directly below the bearings 200. These offsets 103, however, rest when normal against the uprights 101, so that offset arms 104 make an angle of approximately 45° with the vertical, as will be readily seen from Fig. 2. At one end of each rod 102 is rigidly mounted an armature-lever 105 of a tipping relay TR. The tipping relays TR are individual to a line and may be mounted on the frame in any convenient manner. When a relay TR is energized, it tips its rod 102 so that offset 103 is in position to be engaged by an arm of any falling carriage. Carried 75 on each armature 105 is a rod 106 placed so as to close contact springs 107 when the armature 105 is pulled up.

70

Carried on each armature 105 is a rod 106 placed so as to close contact springs 107 when the armature 105 is pulled up. The terminal strips 108, in which terminate one side of a subscriber's line, are carried in slots 204 of uprights 101, and have contact springs 109 spaced at intervals corresponding to the trunk wires and carriages. The contact springs 109 are in contact with arm 203 of the carriage during a conversation.

90

The relays TR are divided into groups, first a group at one end of the terminal rods and then a group at the other end. The relays in a group are staggered enough to permit of their being placed side by side. The number of relays in a group, as shown in Fig. 1, is three, but such number will vary with the size of the relays and the distance between the line rods. This arrangement of relays allows close spacing of the line rods, which reduces to a minimum the necessary travel of a carriage in traversing a given number of rods.

100

The wires 110 and 111, in which the trunks terminate, are stretched between horizontal bars 205 and 206 which are part

105

110

of the frame. They are insulated from the frame and may be held in any well-known manner. The leads to the trunks may be attached at either the top or bottom of wires 110 and 111, being shown at the bottom in Fig. 2.

Slidably mounted on each pair of wires 110, 111 is a carriage 113. This carriage is made of some conducting material and is in electrical connection with wire 110 at the bearings 211, but is insulated from wire 111 by insulating rings 210. The carriage 113 is made light so as to be easy of acceleration and so as to stop without appreciable jar. Arms 114, 115 and 116 are rigidly mounted on carriage 113 as shown in the drawings. A connector arm 201 is pivoted at its upper end on the pin 209 which is mounted on the carriage. The arm 201 is held in normal position by a flat V-shaped spring 208, and is positioned so that its jaws 202 will engage, during the fall of the carriage, the offset 103, of any terminal rod 102 which has been displaced owing to the coming in of a call from its associated line. The metal strip 203 is held on the arm 201, but insulated from it by the insulation 207. This strip is arranged to make connection between a contact spring 109 and wire 111 when the arm 201 has been raised by engagement with a terminal rod.

A starting magnet SM is provided for each switch, one of those shown being designated SM₁ and the other SM₂. When referring to either the designation SM is used. The magnet SM is mounted on the frame in such a position that, when it is de-energized, its armature 124 will support the arm 114, thus holding the carriage 113 in normal position. At this time, the contact springs 128 are held closed. When SM is energized, the armature 124 is moved from beneath arm 114, allowing the carriage to fall, and opening contact springs 128. The magnets SM are made slow to release for a purpose to be explained hereinafter.

For restoring the switch, the drums 127 and 129 and wire 112 are provided. The drums 127 are loosely mounted on the shaft 128 which is supported by horizontal frame members 207. A spiral spring 130 tends to push each drum 127 along the shaft so that a stop 212 on the drum will be engaged by a catch 126, fixed on the shaft, but the drum 55 is normally kept away from such engagement by a bell crank 117 pushing against it. The bell crank 117 is pivoted on the pin 118 which is fixed to the frame, is provided at its lower end with two pins 119 and 120, and 60 is normally held by the armature 121 of restoring magnet RM. One magnet RM is associated with each switch. Its armature 121 has at one end a barbed head 122 which holds the pin 120 when the armature is retracted, and which holds the pin 119 when

121 is attracted. The upper face of the barbed head 122 is shorter than the lower, so that, upon the second retraction of 121, the pin 120 will slide over the lower face and release the bell crank 117.

A wire 112, attached at its upper end to drum 127, passes through a slot in arm 116 of the carriage 113 to drum 129, on which it is normally wound. The drums 129, of which there is one for every switch, are 75 loosely mounted on a shaft supported by bars 206 of the frame. Spiral springs 131 oppose the unwinding of wire 112 from drum 129, and cause it to be rewound when its upper end is released. A block 125, fastened to the wire 112, will engage arm 116 when wire 112 is being wound on drum 127, and will lift the carriage 113 back to normal position.

The shaft 128 may be constantly rotating 85 or it may be started every time it is necessary to restore a switch, any simple means being used to control its rotation. In the system shown and described herein, the shaft will be considered as constantly rotating 90 in such a direction as to wind the wire 112 on the drum 127 when bell crank 117 allows catch 126 to engage stop 212. The arm 115 engages bell crank 117 when carriage 113 has been lifted nearly to normal, 95 pushing it back so that the pin 120 will be caught by the head 122 of armature 121 which is in its retracted position during the upward travel of the carriage. The arm 115 also holds the off-normal springs ON in normal position when the carriage is at the top of its travel, and allows them to assume their off-normal position when the carriage falls.

A restoring relay RR for each switch controls the circuit of the restoring magnet RM. Individual to each subscriber's line is a line relay LR for controlling the tipping relay TR.

The operation of the switch is as follows: 110 When the subscriber takes his receiver off the hook, the line relay LR is energized from battery, left-hand winding of LR, wire 1, subscriber's substation, wire 2, right-hand winding of relay LR to ground, and closes 115 at its front contact a circuit from battery through relay TR to ground. Relay TR tips the rod 102, as has been described, and closes contacts 107. This closes a circuit for the starting magnet SM from battery, contact springs 107, off-normal spring ON in normal position, magnet SM to ground. Magnet SM, pulling up its armature 124, releases carriage 113 and opens contact springs 128. The carriage 113 falls until the arm 201 engages in jaws 202 the tipped rod 102. Relay TR is still energized, and therefore cushions the shock of the carriage which, however, replaces rod 102 in normal position. When the arm 201 seizes the rod 130

102, it is raised so that strip 203 will make contact at its lower end with the spring 109 and at its upper end with the wire 111, completing the talking circuit from the subscriber to an operator's position, or to a first selector. From this point the call is completed in the usual manner.

As soon as the arms 201 and strip 203 have connected the subscriber's set with the trunk, the restoring relay RR is energized from battery through the restoring relay, wire 111, strip 203, strip 108, wire 4, wire 1, subscriber's set, wires 2 and 3, rod 102, arm 201, carriage 113, wire 110, trunk wire 5 to ground. The relay RR closes at its front contact a circuit from battery through restoring magnet RM, bottom spring of off-normal spring ON to ground. The magnet RM thereupon becomes energized and pulls 15 up its armature 121, allowing barb 122 to catch pin 119 and hold it throughout the conversation. At the end of the conversation, when the subscriber hangs up, he breaks at his switchhook the circuit holding 20 up relay RR, which thereupon allows its armature to fall back. The armature opens at its front contact the circuit of the magnet RM, which then deenergizes. When armature 121 falls back, it does not catch 25 the pin 120, but allows it to slide over the lower face of barb 122, and spring 130 forces the drum 127, with its stop 212, into engagement with the catch 126. The shaft 128, which is constantly rotating, begins to wind 30 the wire 112 on drum 127. When block 125 reaches arm 116, it lifts the carriage 113 back to normal position. Just before normal position is reached, the arm 115 forces 35 back bell crank 117 so that armature 121 will engage pin 120. At its upper end, bell crank 117 moves the drum 127 away from the catch 126, whereupon springs 131 cause 40 the drum 129 to wind back the wire 112, and the switch is ready for the next call.

If a second call comes in while the first switch is in use, a circuit will be closed from battery, contact springs 107, off-normal spring ON, springs 128, off-normal spring ON, starting magnet of the next switch 45 SM₂ to ground. The energization of magnet SM₂ will cause a connection to be completed in the same manner as has been previously described for the first switch.

It is to be noted that contact springs 107 remain closed during the fall of the carriage 50 113, so that, to prevent the starting of another switch, the starting circuit is broken at spring 128. In order that these springs shall remain open during the fall of the carriage, starting magnet SM is made slow to 55 release, and will hold its armature up until the calling line has been seized.

What is claimed is:

1. In an automatic switch, a gravity operated carriage, an arm on said carriage, stop members normally positioned out of the path of movement of said carriage arm, means for moving a selected stop member into the path of movement of said arm, and means controlled by the engagement of an arm with the selected stop member for moving said stop member out of the path of movement of arms on subsequently operated carriages. 65

2. In an automatic switch, a gravity operated carriage, an arm on said carriage, stop members normally positioned out of the path of movement of said carriage arm, electromagnetic means for moving a selected stop member into the path of movement of 70 said arm and holding it in said path, and means controlled by the engagement of an arm with a selected stop member for moving said stop member out of the path of movement of arms on subsequently operated carriages and stopping the carriage whose arm is engaged, said electromagnetic means serving to dissipate the momentum of said falling carriage. 80

3. In an automatic switch, movable rods 90 in which subscribers' lines terminate, a rod being associated with each line, gravity operated carriages in which trunk lines terminate, said carriages being adapted when released to traverse and make contact with 95 said rods, means operated on the initiation of a call for positioning a subscriber's rod in the path of any carriage which may fall, and means actuated upon the operation of said means for releasing a carriage. 100

4. In an automatic switch, movable rods and fixed terminal strips in which subscribers' lines terminate, a rod and a strip being associated with each line, gravity operated carriages in which trunk lines terminate, each carriage being provided with means for connecting a selected rod and strip to the trunk line with which said carriage is associated, means for holding each carriage in normal position when its associated trunk line is idle, said means operating to prevent the fall of any other carriage during the fall of its associated carriage, means for moving a subscriber's rod into selectable position upon the initiation 115 of a call, and means operated upon the actuation of said rod-moving means for rendering ineffective the holding means of a carriage associated with an idle trunk. 110

In witness whereof, I hereunto subscribe 120 my name this 16th day of November, A. D. 1916.

FRANK A. LUNDQUIST.
